(57) **CLAIM**

I claim the ornamental design for lotion dispenser, as shown and described in the drawings.

DESCRIPTION

FIG. 1 is a side perspective view of a lotion dispenser in accordance with the new design;

FIG. 2 is a side elevational view thereof;

FIG. 3 is a front elevational view thereof;

FIG. 4 is a rear elevational view thereof; and,

FIG. 5 is a top plan view thereof.

The broken lines in the drawings are for illustrative purposes only and form no part of the claimed design.
